UNITED STATES PATENT OFFICE

2,560,954

BASIN DRAIN SPILLWAY

Alexander F. Jackson, East Orange, N. J.

Application January 9, 1947, Serial No. 720,949

2 Claims. (Cl. 4—206)

1

A prime object of the present invention is to provide a novel and improved drain spillway that permits the desired mixing of hot and cold water in a basin which has separate hot and cold water faucets without mixing means.

Another object is to provide a drain spillway which shall embody novel and improved features of construction whereby to retain in the basin a body of water of predetermined depth for washing, rinsing and draining purposes and at the same time allow the water to flow continuously into the basin from the supply faucet or faucets and away therefrom through the usual drain pipe.

Still another object is to provide a device of this kind that shall include a novel and improved construction and combination of a tubular body having a fully open upper end and a strainer to permit suds, lather, grease or the like to drain away freely but to prevent articles from falling into or being carried by the water into the drain pipe.

Further objects are to provide a device of this kind with novel and improved means for firmly holding it in operative position but permitting easy and quick removal when desired; and thus to provide the device with a tubular body having a fully open top end and a base having suction faces for engagement with the bottom of the basin for firmly holding the device detachably in position on the bottom surfaces of basins having various types of drain openings including those having valves that rise upwardly therefrom.

Other objects of the present invention are to provide a drain spillway that is compact, simple in construction, economical to manufacture, portable, easily carried in a traveling bag for use in a hotel, easily mounted in the ordinary type basin and easily removed therefrom.

The invention will be better understood from the description thereof to follow taken in connection with the accompanying drawing in which—

Figure 1 is a part elevational and part sectional view of a basin showing a drain spillway embodying my invention in position over the drain pipe.

Figure 2 is an enlarged sectional view of the drain spillway.

Figure 3 is a top plan view thereof.

Referring to Figure 1, the improved drain spillway 1 is shown installed in a basin or sink 2 of ordinary construction having a drain opening 3 adjacent its side wall 4 and communicating with one end of a drain pipe 5 which receives and car-

ries away the water drained from the basin. Only a single water faucet 6 positioned above the drain opening is shown but the invention contemplates the use of at least two separate faucets, one for hot and the other for cold water.

The spillway is a single unit formed of flexible or resilient material such as rubber or rubber composition. It comprises a relatively thin and flat circular base portion 7 and an integral upright tubular body portion 8 with a fully open top disposed eccentrically of the base and within the edges thereof. The bottom of the tubular body portion extends below the base forming an annular flange 9. The outer wall of the tubular portion tapers slightly downwardly and outwardly. The base is formed with a downwardly extending margin or edge portion 10 extending therearound and spaced inwardly therefrom is another semi-circular downwardly extending flange portion 11 which may be slightly wider and shallower than the margin 10. The margin 10 and the flange portion 11 together with one half of the circular flange 9 of the tubular body portion provide a space or annular suction cup 12 whose bottom comprises a substantially annular suction face 13 on the base which tapers to a narrow point between the circular flange and the margin 10 as indicated at 14. The semi-circular flange 11 and the other one-half of the annular flange 9 provide a space or suction cup 15 whose bottom comprises a crescent-shaped suction face 16 on the base. The annular flange 9, margin or edge portion 10 and flange 11 are sufficiently pliable and flexible to ensure that they will conform to the surface to which they are to be engaged notwithstanding any irregularities in such surface.

About midway its length, the tubular body portion is formed with a strainer comprising a transverse wall 17 integral with the side wall of said tubular body portion. The wall is provided with a plurality of slots 18 adjacent the side wall and with a plurality of various sized perforations or holes 19 between said slots. This transverse wall may be slightly dome-shaped to facilitate drainage of the water therefrom. It makes the tubular body portion more rigid preventing it from collapsing. The depth of the tubular body portion determines the depth of the body of water retained in the basin and it may be made as high as desired within the confines of the depth of the basin.

In use when it is desired to install the spillway in the basin, the spillway is fitted over the drain opening 3 with the flange portion 9 of the tubu-

lar body portion resting on the upper peripheral edge of the opening as indicated at 20, and with the margin 10 and flange 11 resting on the bottom of the basin at points spaced outwardly of said opening. Downward pressure is then applied to the tubular body portion thereby forcing the annular flange portion 9 into intimate contact with the upper edge of the opening and forming a seal thereat, and at the same time forcing the margin 10 and flange 11 together with the suction faces 13 and 16 into intimate close contact with the bottom of the basin and creating a vacuum between said faces and the bottom of the basin. The suction action between the suction face 13 and the bottom of the basin is sufficient to hold the spillway firmly in position but this suction action is augmented by the suction between the suction face 16 and the bottom. Thus a double seal is produced which firmly holds the spillway in operative position.

The water from the faucet or faucets 6 is then allowed to flow freely into the basin and is retained therein until the depth thereof reaches the top of the spillway as indicated by the dot-dash line 21 of Figure 1 which is sufficient for ordinary washing and rinsing purposes. Thereafter the water may continue to flow into the basin from the faucet or faucets as long as desired and it will be discharged from the basin through the spillway as fast as it is delivered thereto while retaining the desired depth of water in the basin. The water in the basin can readily be tempered by permitting the water from the hot and cold water faucets to mix and by allowing the too hot or too cold mixed-water to overflow into the spillway until the proper temperature is reached. Anything floating on the surface of the water in the basin such as suds, lather, grease or the like may be readily floated over the spillway into and through the openings and slots in the strainer into the drain pipe, or toothpaste or mouthwash may be deposited directly through the fully open top end of the tubular body. This eliminates the necessity of emptying the entire contents of the basin down the drain pipe and thus is more economical and time saving. Furthermore, the location of the strainer intermediate the length or a substantial distance below the top of the tubular body portion, provides a water head above the strainer to continuously flush or carry off suds, scum, etc. through the strainer and also permits a drain valve to rise upwardly freely from the drain opening. Solid objects are prevented from passing into the drain pipe by the solid portions of the transverse wall 17.

When it is desired to remove the spillway, the

tubular body portion serves as a handle whereby the base portion can be pulled outwardly and twisted to deform the outer margin 10 and flange 11 slightly in order to destroy the vacuum areas and permit the device to be removed.

The spillway is easily transported and may be readily installed in any ordinary type of basin without altering either the spillway or the basin.

Changes in details might be resorted to without departing from the spirit or principle of the invention.

What I claim is:

1. A drain spillway for a basin that has a drain opening in the bottom thereof, comprising a thin substantially flat flexible base having a continuous annular downwardly projecting flange extending throughout its edges, a tubular portion integral and eccentric with respect to said base and having its upper end portion fully open and projecting upwardly from said base and having its lower end projecting downwardly from said base beyond the plane of said marginal flange within and spaced from said marginal flange, whereby said spillway may be set with both said marginal flange and said lower end of the tubular portion in contact with said bottom of the basin and with said lower end of the tubular portion in closely encircling relation to said drain opening even when said opening is close to a side wall of the basin.
2. A drain spillway for basins as defined in claim 1, with the addition of an integral wall extending across the interior of said tubular body portion a substantial distance below the upper end thereof and a substantial distance above the lower end thereof, said wall being formed with a plurality of perforations.

ALEXANDER F. JACKSON.
